Primary Examiner — Kendra Leslie Hamilton

Assistant Examiner — Michael Hoffman

(57) **CLAIM**

The ornamental design for a tracheostoma device as shown and described.

DESCRIPTION

1. Tracheostoma device

1.1 : Back view

1.2 : Back right perspective view

1.3 : Front left perspective view

1.4 : Left view

1.5 : Top view

1.6 : Right view

1.7 : Bottom view

1.8 : Front view

The products as shown in the designs are used as medical aids for tracheotomized or laryngectomized persons, especially enabling the persons to breathe safely after surgery by way of a tracheostomy tube and aids for inserting a tracheostomy tube.

1 Claim, 8 Drawing Sheets
